VACUUM FILLING MACHINE

This invention has for an object to provide a novel and improved vacuum operated bag filling machine particularly adapted for filling flexible bags with finely divided materials in a rapid and superior manner and which embodies novel and improved safety devices for controlling the operation of the machine in the event of the absence of a bag or in the event of displacement of a flexible bag relative to a filling head in a simple and expedient manner.

With this general object in view and such others as may hereinafter appear, the invention consists in the vacuum filling machine and in the various structures, arrangements and combinations of parts hereinafter described and particularly defined in the claims at the end of this specification.

In the drawings illustrating the preferred embodiment of the invention:

FIG. 1 is a plan view of a vacuum filling machine embodying the present invention;

FIG. 2 is a plan view of the lower portion of the machine showing part of the control mechanism;

FIG. 3 is a developed view in side elevation of the filling heads and their elevating platforms and diagrammatically indicating portions of the control mechanism;

FIG. 4 is a diagrammatic view of the pneumatic and electrical controls associated with the filling heads;

FIG. 5 is a cross-sectional view of a vacuum filling head showing a container operated control valve associated therewith; and

FIG. 6 is a plan view of the drives to the filling machine.

In general, the present invention contemplates a novel and improved vacuum operated filling machine, herein shown as provided with shrouded vacuum filling heads, adapted to fill flexible containers, such as bags, with finely divided flowable materials and, in general, comprises an improvement in the vacuum filling machine illustrated and described in the U.S. Pat. No. 2,847,040 to Edward J. McCarthy et al., issued Aug. 12, 1958. Such prior machine comprises a continuously operated rotary machine having a plurality of elevating platforms arranged to receive successive containers delivered thereto and to elevate the same into operative relation to the shrouded vacuum filling heads during the rotary movement of the machine.

In the operation of the present machine successive bags are transferred onto successive elevating platforms by a rotary transfer spider which is arranged to engage and transfer successive bags delivered thereto by a continuously operated conveyor having provision for advancing the bags in predetermined spaced relation and in timed relation to the rotary transfer spider. The bags thus received on their respective elevating platforms are elevated into operative relation to their respective filling heads rotated in alignment therewith, and when bag is fully seated and sealed in a vacuum filling head, the bag is evacuated and filled with the material being packaged. The elevating platform is then caused to be lowered with its filled bag and transferred from its platform onto a discharge conveyor.

In accordance with one feature of the present invention novel and improved bag operated pneumatic control means is provided including means actuated by the upper edge of a fully seated and sealed flexible bag for initiating the filling operation. Thus, if a bag fails to be fully seated in filling position relative to its filling head, indicating that the flexible bag is jammed or otherwise displaced in its shroud, the vacuum filling means remains inoperative for that particular filling head. Also, in such event, means controlled by the bag operated means is arranged to terminate operation of the machine because of failure of the bag to reach its fully elevated position so that the operator may remove the crushed bag from its shroud.

In the normal operation of the machine, when the bag is fully seated and sealed in its shroud and the filling operation is initiated by virtue of the bag operated control means to fill the bag during the continuous rotation in a circular path, the filled

bag is lowered with its elevating platform preparatory to discharging the bag from the machine. However, in the event that the bag becomes stuck in its shroud and is not lowered with its elevator, the container operated control remains in its actuated position beyond a predetermined point in its filling cycle. In such event, provision is also made for terminating the operation of the machine so that the operator may remove the stuck bag from the shroud.

In accordance with another feature of the present invention, provision is made for controlling the operation of the machine in a manner such as to prevent elevation of a particular elevating platform, in the event that a container is absent from the supply in a position to be transferred thereto, while permitting the machine to continue in operation to fill and discharge the preceding and succeeding containers delivered thereto. By permitting continuation of operation of the machine production is increased and wear and tear caused by unnecessary or excessive stopping and starting of the machine is reduced to a minimum. In practice it will be seen that failure of the elevator to rise because of the absence of a bag also fails to actuate the bag operated control means for that particular filling head so that filling operation is not initiated. Thus, the bag operated control means will remain in a position to discontinue operation of the machine, the same as when a bag fails to be fully seated. However, elevator operated control means actuated when the elevator fails to rise and remains in its lowered position is arranged to maintain the machine in operation in the event that a bag is initially absent as will be described.

Referring now to the drawings and particularly to FIG. 1, the present invention is illustrated as embodied in a rotary type machine having a plurality of elevating platforms 10 continuously movable in a circular path and arranged to support successive bags 12 delivered thereto by rotary transfer mechanism indicated generally at 14. As herein shown, the bags are supplied on a conveyor 16 along which they are advanced in spaced relation and in timed relation to be received by rotary transfer elements 18 which are arranged to continue the advance of successive bags onto successive elevating platforms 10. In general, in the operation of the machine the bags are elevated into operative to shrouded vacuum filling heads indicated generally at 20 rotated in alignment with the elevating platforms 10. The elevating platforms 10 are arranged to seal the bags in airtight relation to the filling heads to permit evacuation and filling of the bags during the rotation of the machine whereupon the elevating platforms are lowered with their filled bags and transferred from the platforms by transfer means indicated generally at 22 to deliver successive bags onto a discharge belt 24.

As illustrated in FIG. 6, the drive to the rotary filling machine is taken from a motor driven line shaft 26 which drives a line of successive synchronized package forming, filling and closing machines and, as herein shown, the bag filling machine is driven in timed relation to the other machines in the line through a chain and sprocket drive 28 to a shaft 30 which extends into one side of a gear box 32. The driving connections in the gear box 32 include a worm 34 and worm gear 36, the latter being mounted on a vertical shaft 38 which is also provided with a pinion 40. The pinion 40 is in mesh with an intermediate gear 42 which in turn meshes with opposed gears 44 and 46 for driving the continuously rotated intake and discharge spiders 14 and 22, respectively, of the continuously operated bag filling machine. A third gear 48 in mesh with the intermediate gear is in mesh with a ring gear 50 for rotating the filling heads and elevating platforms of the bag filling machine. Successive bags 12 engaged by the transfer arms 18 are advanced between curved guide rails 52, 54 in timed relation to the arrival of successive elevating platforms 10 of the bag filling machine and the bags delivered to the platforms are then elevated into operative filling position to their respective vacuum filling heads 20. As shown in FIG. 1, the transfer arms 18 are pivotally mounted on a disk 56 fast on the intake spider shaft 58, and each arm is provided with a roller 60 for cooperation with a stationary cam 62 supported

beneath the disk. The cam 62 is designed to maintain the transfer arms 18 in their bag engaging position until the bag is deposited on its elevating platform 10 whereupon the arm 18 is permitted to rock away from the bag to avoid displacement of the same on its elevating platform during the continuous rotation of the transfer arms and the elevating platforms.

As indicated generally in FIGS. 3 and 4, each elevating platform 10 is mounted on and secured to the top of a pneumatically operated sleeve or cylinder 64 slidably supported on an upright post 66 secured to an annular plate 68 rotatable with the machine. The post 66 is provided with a central bore 70 which communicates with an air supply at its lower end and is closed at its upper end by the underside of the elevating platform 10 when the platform is in its lowered position. In operation, when compressed air is permitted to enter the lower end of the central bore 70, the sleeve 64 with its elevating platform 10 is caused to rise on its central supporting post 66 to elevate a bag into operative relation to its individual shrouded vacuum filling head. In general, the elevating means is similar to that shown and described in U.S. Pat. No. 2,847,040, above referred to except as to the control means to be hereinafter described. As herein shown, compressed air is supplied to each elevator through individual valve units 71 connected to a supply header or loop 73 rotatable with the machine, the header air, being connected by a vertical pipe 75 extending to a point above the machine where the pipe is offset to extend in alinement with the center of rotation of the machine. The upper end of the vertical pipe 75 is provided with a stationary adapter 77 arranged to permit rotation of the pipe, and the adapter is connected by a supply pipe 79 to a regulated source of compressed air. Each individual valve unit 71 is provided with an arm 81 having a roller 83 for cooperation with control cams for opening and closing the valves to permit elevation and lowering respectively of the elevating platform as will be hereinafter more fully described. A conduit 85 extends from the valve unit 71 to the lower end of the elevator supporting post 66.

In general, the shrouded vacuum filling heads 20 are also similar to those illustrated and described in the patent above referred to except as to details to be hereinafter pointed out. As shown in FIG. 5, each filling head includes a head portion 72 provided with a material inlet opening 74 and with two suction openings 76 and 78. The head portions 72 are secured to the underside of an annular plate 80 which is in communication with an annular supply hopper 82 secured to the plate. Each filling head further includes a hollow rectangular shroud portion 84 slidably supported in alinement with its head portion on rods 86 depending from the head portion. The upper end of the shroud portion is provided with a bag mouth engaging and sealing section comprising a flexible band 88 of rubber or like resilient material, the band being cemented or otherwise secured to the upper end 90 of the shroud and to a separate rectangular hollow section 92 above the shroud leaving an intermediate preconvoluted connecting portion of the flexible band free. In operation, when a flexible bag 12 is elevated into the shroud portion of the filling head by the elevating platform 10, the upper edges of the mouth of the bag are guided into the relatively narrow space between the filling head portion 72 and the band 88, and upon further upward movement of the elevator 10, the band will be resiliently urged into airtight sealing engagement with the bag at a point below the upper edge of the bag. At the same time, the open bottom of the shroud will be sealed by engagement of the platform 10 with a resilient skirt portion 94 to enclose the bag within the shroud. As shown, there is a space between the interior of the shroud and the exterior of the bag, which space is also evacuated at the same time that the bag is evacuated so as to prevent collapse of the bag.

The vacuum filling operation is performed in a manner similar to that illustrated and described in the patent above referred to wherein the fully seated and sealed bag in the shrouded vacuum filling head 20 is evacuated and filled, the vacuum being controlled by individual cam operated valve

block units 96 associated with each vacuum filling head. As shown in FIG. 4, each valve block 96 is provided with a vacuum supply chamber 98 having a valve opening 100 in communication with a vacuum chamber 102. The supply chamber 98 is connected by a conduit 104 to a hollow cap member 106, see FIG. 1, rotatable about the upper end of a central hollow supporting sleeve, the lower end of which is connected to a vacuum pump or other source of reduced air pressure as shown in U.S. Pat. No. 2,847,040 to which reference may be made. The vacuum chamber 102 is provided with a conduit 108 connected to the head portion 72 and is also provided with a valve 110 slidably mounted in the valve block 96 and arranged to close the opening 100 between the chambers 102 and 98. The valve 110 is connected to an air cylinder 115 forming a part of the pneumatic control circuit for initiating the filling operation in response to bag operated sensing means as will be hereinafter described.

The vacuum chamber 98 is also provided with a valve 112 slidably mounted in the block 96 and arranged to cooperate with a port 114 to which the vacuum supply pipe 104 is connected. The outer end of the valve stem is provided with a forked member 116 having a roller 118 arranged to cooperate with a cam 120 fast on the central supporting sleeve. A spring 122 surrounding the stem of the forked member 116 and interposed between the shoulder of the forked member 116 and the valve block 96 is arranged to urge the valve 112 to its open position, and the cam 120 is arranged to move the valve to its closed position to close the port 114 and to cut off the suction to the vacuum chamber 98.

The valve block 96 is also provided with an atmospheric chamber 124 which has an opening 126 and a port 128 connected by a conduit 130 to the vacuum filling head portion 72. A valve 132 cooperating with the port 128 is arranged to control the atmosphere connection 130 to the head portion 72 and is also provided with a valve stem having a forked member 134 having a roller 136 cooperating with a cam 138 fast on the central supporting sleeve. A similar spring 122 is arranged to urge the valve 132 to its open position. During the filling operation the cam 120 effects opening of the valve 112 to permit the bag to be evacuated and the material withdrawn from the supply through the inlet opening 74 into the bag. The space within the shroud is also evacuated at this time through a conduit connection 140 from the head portion 72 to an opening in the shroud to equalize the pressure within and without the flexible bag during the filling operation. Substantially simultaneously with the opening of the valve 112, the cam 138 effects closing of the atmospheric valve 132, the cams 120, 138 being arranged to effect alternate opening and closing of the valves subjecting the filling head alternately to the suction and the atmosphere during the filling operation.

Referring now to FIGS. 4 and 5, in accordance with the present invention, novel bag operated pneumatic control means is provided for initiating the filling operation and for controlling the operation of the machine in the event of displacement or absence of a bag. As herein shown, the control means includes a pivotally mounted sensing arm 142 which extends laterally into the filling head at a point above the shroud sealing portion 92, the inner end of the arm having a recessed element 144 arranged in the path of the upper edges of a fully seated bag in the filling head. The arm 142 is mounted on a stud 146 carried by a bracket 148 secured to the underside of the annular supporting plate 80. A second arm 150 extending at right angles to the arm 142 is arranged to cooperate with a sensing valve unit 152 having an operating arm 154 which carries a roller 156 engageable with said second arm. The sensing valve unit 152 forms a part of the pneumatic control circuit for controlling the cylinder 115 which operates the valve 110, the valve unit 152 being normally closed and arranged to be opened by the sensing arm 142 when the latter is rocked upwardly by the upper edge of a fully seated bag.

As illustrated in FIG. 4, each sensing circuit, one of which is diagrammatically indicated at 160, includes a conduit 162 ex-

tending from a header 164 which latter is connected by a pipe 166 to the header 73. The conduit 162 leads to the sensing valve 152 and a conduit 168 leads from the sensing valve 152 to a tee 170, the upper end of which is provided with a normally open pilot valve 172 and the lower end of which is provided with a normally closed pilot valve 174. The pilot valves 172, 174 are supplied with air from conduit connections 176, 178 from the conduit 162 and are connected by conduits 180, 182 respectively to the upper and lower ends of the two-way air cylinder 115. It will be observed that in operation when the valve 152 is closed, air is directed from conduit 162 through the normally open pilot valve 172 and conduit 180 to the upper end of the cylinder 115 to urge the valve 110 down to close the opening 100 to cut off the vacuum supply to the filling head. However, when the bag is fully seated in its shroud and the arm 144 is rocked upwardly by the top edge of the bag, the valve 152 is opened and air is directed through conduit 168 and tee 170 to close the normally open valve 172 and open the normally closed valve 174. As a result, the valve 110, is elevated to uncover the opening 100 to afford communication between the vacuum chambers 98 and 102 to initiate the filling operation. During continued rotation of the filling head, the cam operated valves 112, 132 are operated alternately as above described to complete the filling operation. Subsequently, when the elevator is lowered with its filled bag, the valve 152 is closed and the pilot valves 172, 174 return to their normal position to effect closing of the valve 110 to discontinue the filling operation.

From the description thus far, it will be apparent that if no bag is present in the shroud, or if the bag is not elevated to its fully seated position, indicating that it is crushed or crumpled within the shroud, the sensing valve 152 will not be opened, and the filling operation will not be initiated. In accordance with another feature of the present invention provision is made for discontinuing the operation of the machine in the event that a bag is not fully elevated into the shroud. As diagrammatically illustrated in FIG. 4, the conduits 180, 182 connected between the cylinder 115 and the normally open and normally closed valves 172, 174, respectively, are connected by conduits 184, 186 to the upper and lower ends of a two-way air cylinder 188 whose piston rod 190 is connected to a switch cam 196 pivotally mounted at 194. A second switch cam 192 also mounted on the pivot 194 is arranged to be rocked with the first cam 196. In practice, the switch cams are mounted in spaced relation, that is, one above the other, the upper cam 192 being aligned with a stationary switch 198 and the lower cam 196 being aligned with a stationary switch 200. The switches 198, 200 may be mounted on the machine frame and, as shown in FIG. 4, the switches are included in a circuit to a motor starter coil 202. In operation, when the bag fails to be elevated into the shroud and the valve 152 remains closed, air is directed from conduit 162, conduit 176, through the normally open pilot valve 172, conduits 180 and 184 to the upper end of the air cylinder 188 to effect rocking of the switch cams to the left to position the cam 192 in alignment with the stationary switch 198. At the same time, cam 196 is rocked out of alignment with switch 200. As a result, when the valve 152 fails to be opened because of a crumpled bag, the cam 192 will operate switch 198 to stop the machine.

On the other hand, when the bag is fully seated so as to open the valve 152 and to reverse the operation of the pilot valves, air is directed from conduits 162, 178, pilot valve 174 and conduits 182, 186 to the lower end of the two-way air cylinder 188 to effect rocking of the switch cams to the right. As a result, the cam 192 will be rocked out of the path of the switch 198 and the machine will not be stopped.

It will be understood that there are a pair of cams 196, 192 associated with each filling head. The positions of the stationary switches 198, 200 in the circular path of movement of the filling heads is shown in FIG. 2. Although the cams 196, 192 are rocked to switch opening position in case of failure to open valve 152 as soon as the elevator reaches its uppermost position, the switch 198 will not be opened until the particular

filling unit arrives at the position where the switch 198 is located. The switch 198 is thus located to effect stopping of the machine to present the filling head at a convenient location when the machine comes to rest to permit the operator easy access to the filling head to remove the crumpled bag.

Provision is also made for stopping the machine in the event that the filled bag is not lowered with its elevator at the end of a normal filling cycle. It will be seen that when a bag to be filled is fully seated the valve 152 opened, the switch cams will be rocked to the right as shown in FIG. 4, in which position cam 196 is rocked into a position to open switch 200 unless the switch cams are returned to their normal position. It will also be seen that at the end of a normal filling cycle when the filled bag is lowered with its elevator, the sensing valve 152 will again be closed causing the cams 196, 192 to be again shifted so as to rock cam 196 out of alignment with switch 200 and thus avoid stopping of the machine. However, if the bag fails to be withdrawn with its elevator indicating that the bag is stuck in its shroud, the valve 152 will remain in its open position so that the cams 196, 192 will remain in the position shown in FIG. 4 to operate switch 200 thus opening the circuit to the motor starter coil 202 to stop the machine. While the switch 200 is shown in FIG. 2 in a position removed from the position where the elevator starts its downward movement, it will be understood that switch cam unit 196, 192 associated with the particular filling head under discussion is located in a position to engage the switch 200 when failure of a bag to drop with its elevator is detected. When the machine comes to rest and the operator manually withdraws the bag from the shroud, the valve 152 is again closed and the switch cams are again rocked to their normal position.

As above described, a valve unit 71 is associated with each elevating unit, each valve having an inlet connected by a conduit 210 leading from the header 73 and an outlet connected by the conduit 85 leading to the supporting post 66 on which the cylinder or sleeve 64 is mounted. The valve 71 is also provided with an operating arm 81 having a roller 83 arranged to cooperate with cam 212 mounted at the end of a piston rod 214 operating in an air cylinder 216. Compressed air is supplied to the cylinder by a pipe 218 leading from a normally open solenoid valve 220, the valve also being connected to a supply of compressed air by a pipe 222.

In operation, the cam 212 is normally extended, as shown, to effect rocking of the arm 81 and opening of the valve 71 to cause elevation of a platform and initiate a filling operation when a bag is elevated into the filling head to open the valve 152. Subsequently, when the filling operation is completed, the valve arm 81 is rocked to its closed position by a stationary cam 224, see FIG. 2, attached to the machine frame to permit lowering of the elevator. As illustrated in FIG. 3, the pneumatic elevation of the platform 10 is controlled by a stationary cam 246 and the lowering of the platform is controlled by a cam 248, each cam cooperating with a roller 250 carried by each sleeve or cylinder 64 of the elevating units.

In accordance with another feature of the invention, provision is made for detecting the presence of a bag entering the machine and for preventing elevation of a platform in the event that a bag is missing from the line of spaced bags entering the machine, such detecting means comprising a photoelectric control indicated generally at 226 arranged to close the normally open solenoid operated valve 220 so as to permit the air cylinder 216 to exhaust, thus retracting the normally extended cam 212. Opening of the valve 71 is thus prevented and the elevating platform remains in its lowered position. As diagrammatically indicated in FIGS. 2 and 4, the photoelectric control 226 for detecting the absence of a bag includes a light source 228 and a photocell 230 connected to a photoelectric relay 232. The light source 228 is located below the container supporting disk, and the latter is provided with an opening 234 through which the beam from the light source is directed to the photocell when a bag is missing, the beam being cut off by the presence of a bag. It will be noted that the position of the opening 234 in the transfer mechanism for de-

tecting an incoming bag is such that a continuously moving bag in such position will be transferred onto the continuously moving elevating platform numbered 1 when the latter arrives at the bag receiving position. Provision is made for energizing the photocell 230 in timed relation to the movement of the bag, that is, the photocell is arranged to transmit signals only at times when a bag should be in the position to be detected, these signals being blocked during intervals between bags. As herein shown, the timing is accomplished by a normally open switch 236 connected to the photoelectric relay 232, the switch being arranged to be closed by the high spots of a cam 238 secured to and rotatable with the shaft 240 on which the discharge mechanism 22 is mounted.

From the description thus far, it will be seen that in operation if a bag is absent at the opening 234 the photoelectric relay 232 will energize the normally open solenoid valve 220 to close the same, thus retracting the air operated cam 212 and preventing opening of the valve 71 so that the elevator platform 10 remains in its lowered position. Since the elevator does not rise, the air valve 152 is not opened and a filling operation will not be initiated. Under ordinary conditions, when the valve 152 remains closed, the air operated cam members 196, 192 are not rocked so that the cam 192 is alignment with switch 198 would effect stopping of the machine. However, since it is not necessary to stop the machine when a bag is absent, provision is made in such event for maintaining the motor circuit closed when the switch 198 is opened. This is accomplished by a cam piece 242 secured to the elevator which is aligned with a normally open switch 244 when the elevator remains in its down position. The switch 244 is supported on the machine frame and is wired in parallel with the switch 198 so that when the normally closed switch 198 is opened by the cam 192, the elevator cam 242 effects closing of the switch 244 to maintain the circuit closed until after switch 198 is again closed.

From the above description it will be seen that the present vacuum filling machine is provided with novel container operated control mechanism including a pneumatic control circuit having a trip element extended within a filling head arranged to be engaged by the upper edge of a fully seated bag, said pneumatic control circuit having a sensing valve actuated by said trip element to initiate a filling operation. It will be seen that failure of a bag to be elevated into its fully seated position will not actuate the sensing valve and as a result a filling cycle will not be initiated. Provision is also made in response to failure of the sensing valve to be actuated for discontinuing operation of the machine so that the bag which failed to be fully elevated may be removed.

It will also be seen that failure of a filled bag to be lowered with its elevator from the filling head will maintain the sensing valve actuated and that in such event provision is also made for terminating the operation of the machine so that the struck bag may be removed. Finally, it will be seen that novel provision is made for detecting the absence of a bag in the supply of spaced bags being delivered to the machine, and that means responsive to the absence of a bag is arranged to prevent elevation of a bag supporting platform and thus prevent actuation of the sensing valve so that a filling cycle will not be initiated. It will also be seen that the elevating platform which failed to be elevated will continue in its lowered position throughout the cycle, and that provision is made for preventing termination of operation of the machine when a bag is initially absent from the line and the elevating mechanism is maintained in its lowered position.

While the preferred embodiment of the invention has been herein illustrated and described, it will be understood that the invention may be embodied in other forms within the scope of the following claims.

I claim:

1. In a continuously operated rotary vacuum filling machine, in combination, vacuum filling means including a plurality of vacuum filling heads, a plurality of elevating platforms cooperating with said filling heads for supporting flexi-

- ble bags, pneumatically operated means for elevating the platforms to present the bags into operative relation to their respective filling heads, and pneumatically operated control means associated with each filling head including an air circuit and a container operated sensing valve in said air circuit having a movable actuating member cooperating therewith arranged to be engaged by the upper edge of said flexible bag to effect opening of the valve when the bag is elevated to its fully seated position in its filling head for actuating said vacuum filling means to initiate a filling operation, said actuating member adapted to be moved into operative engagement with said valve by a minimum of pressure exerted by the edge of the flexible bag, said vacuum filling means including a cylinder operated vacuum valve in said air circuit associated with its filling head, and a pair of pilot valves in said air circuit cooperating with said cylinder, said bag sensing valve controlling said pilot valves to effect operation of the vacuum filling means to initiate the filling operation when the bag is fully seated.
2. In a continuously operated rotary vacuum filling machine, in combination, vacuum filling means including a plurality of vacuum filling heads, a plurality of elevating platforms cooperating with said filling heads for supporting flexible bags, pneumatically operated means for elevating the platforms to present the bags into operative relation to their respective filling heads, and pneumatically operated control means associated with each filling head including an air circuit and a container operated sensing valve in said air circuit having a movable actuating member cooperating therewith arranged to be engaged by the upper edge of said flexible bag to effect opening of the valve when the bag is elevated to its fully seated position in its filling head for actuating said vacuum filling means to initiate a filling operation, said actuating member adapted to be moved into operative engagement with said valve by a minimum of pressure exerted by the edge of the flexible bag, wherein said pneumatically operated control means includes a cylinder operated vacuum valve in said air circuit associated with each filling head, and a pair of pilot valves in said air circuit cooperating with said cylinder, said bag sensing valve controlling said pilot valves to effect operation of the vacuum filling means to initiate the filling operation when the bag is fully seated, said air cylinder comprising a two-way cylinder and the pilot valves including a normally open and a normally closed valve connected to the two-way air cylinder, said vacuum valve being closed to render the filling means inoperative when the sensing valve is closed, opening of said sensing valve effecting reversal of operation of said pilot valves to effect opening of the vacuum valve and initiation of the vacuum filling operation.
3. In a continuously operated rotary vacuum filling machine, in combination, vacuum filling means including a plurality of vacuum filling heads, a plurality of elevating platforms cooperating with said filling heads for supporting flexible bags, pneumatically operated means for elevating the platforms to present the bags into operative relation to their respective filling heads, and pneumatically operated control means associated with each filling head including an air circuit and a container operated sensing valve in said air circuit arranged to be opened by the bag when the latter is elevated to its fully seated position in its filling head for actuating said vacuum filling means to initiate a filling operation including drive means for rotating said vacuum filling means, said drive means including an electric circuit and a motor in said circuit, a normally closed stationary switch in said circuit, and switch operating means carried by each filling means and controlled by said sensing valve arranged to cooperate with said switch, said sensing valve in its closed position arranged to dispose said switch operating means in a position to open said switch to discontinue the circuit to the motor in the event that a bag is not elevated to its fully seated position in its filling head.
4. In a continuously operated rotary vacuum filling machine, in combination, vacuum filling means including a plurality of vacuum filling heads, a plurality of elevating plat-

forms cooperating with said filling heads for supporting flexible bags, pneumatically operated means for elevating the platforms to present the bags into operative relation to their respective filling heads, and pneumatically operated control means associated with each filling head including an air circuit and a container operated sensing valve in said air circuit arranged to be opened by the bag when the latter is elevated to its fully seated position in its filling head for actuating said vacuum filling means to initiate a filling operation including drive means for rotating said vacuum filling means, said drive means including an electric circuit and a motor in said circuit, a normally closed stationary switch in said circuit, and a movable switch operating cam associated with each filling head and controlled by said sensing valve to dispose the cam out of operating alignment with said switch when a bag is fully seated in its filling head, said cam remaining in its aligned position to open said switch to discontinue the circuit to the motor in the event that the bag is not fully elevated into its filling head.

5. In a continuously operated rotary vacuum filling machine, in combination, vacuum filling means including a plurality of vacuum filling heads, a plurality of elevating platforms cooperating with said filling heads for supporting flexible bags, pneumatically operated means for elevating the platforms to present the bags into operative relation to their respective filling heads, and pneumatically operated control means associated with each filling head including an air circuit and a container operated sensing valve in said air circuit arranged to be opened by the bag when the latter is elevated to its fully seated position in its filling head for actuating said vacuum filling means to initiate a filling operation including drive means for rotating said vacuum filling means, said drive means including an electric circuit and a motor in said circuit, a normally closed stationary switch in said circuit, and movable switch operating means carried by each filling means and controlled by said sensing valve arranged to cooperate with said switch, said sensing valve in its open position arranged to dispose said switch operating means in a position to open said switch to discontinue the circuit to the motor in the event that a filled bag fails to be lowered with its elevating platform.

6. In a continuously operated rotary vacuum filling machine, in combination, vacuum filling means including a plurality of vacuum filling heads, a plurality of elevating platforms cooperating with said filling heads for supporting flexible bags, pneumatically operated means for elevating the platforms to present the bags into operative relation to their respective filling heads, and pneumatically operated control means associated with each filling head including an air circuit and a container operated sensing valve in said air circuit arranged to be opened by the bag when the latter is elevated to its fully seated position in its filling head for actuating said vacuum filling means to initiate a filling operation including drive means for rotating said vacuum filling means, said drive means including an electric circuit and a motor in said circuit, a normally closed stationary switch in said circuit, a movable switch operating cam associated with each filling head, means including an air cylinder in said air circuit controlled by said sensing valve for moving its cam into operating alignment with said switch when the sensing valve is opened upon elevation of a bag into its fully seated position, said air cylinder effecting movement of the cam out of alignment with its switch upon lowering of a filled bag with its elevating platform and closing of said sensing valve, said sensing valve remaining in its open position to maintain its cam in switch opening position in the event that a filled bag fails to be lowered with its elevating platform.

7. In a continuously operated rotary vacuum filling machine, in combination, vacuum filling means including a plurality of vacuum filling heads, a plurality of elevating platforms cooperating with said filling heads for supporting flexible bags, pneumatically operated means for elevating the platforms to present the bags into operative relation to their respective filling heads, and pneumatically operated control means associated with each filling head including an air circuit

5 and a container operated sensing valve in said air circuit arranged to be opened by the bag when the latter is elevated to its fully seated position in its filling head for actuating said vacuum filling means to initiate a filling operation, said pneumatically operated elevating means including an air supply and an elevator valve associated with each elevator to admit air to effect elevation of a platform when the valve is opened and to release air to permit lowering of the platform when the valve is closed, means normally positioned to open said elevator valve, means arranged in the path of said elevator valve for closing the same at the end of a filling operation, means for detecting the presence of a bag being delivered to an elevating platform, and means responsive to said detecting means for changing the position of said elevator valve opening means to prevent opening of said elevator valve when a bag is found to be absent whereby to prevent elevation of said elevating platform.

8. In a continuously operated rotary vacuum filling machine, in combination, vacuum filling means including a plurality of vacuum filling heads, a plurality of elevating platforms cooperating with said filling heads for supporting flexible bags, pneumatically operated means for elevating the platforms to present the bags into operative relation to their respective filling heads, and pneumatically operated control means associated with each filling head including an air circuit and a container operated sensing valve in said air circuit arranged to be opened by the bag when the latter is elevated to its fully seated position in its filling head for actuating said vacuum filling means to initiate a filling operation, said pneumatically operated elevating means including an air supply and an elevator valve associated with each elevator to admit air to effect elevation of a platform when the valve is opened and to release air to permit lowering of the platform when the valve is closed, means normally positioned to open said elevator valve, means arranged in the path of said elevator valve for closing the same at the end of a filling operation, means for detecting the presence of a bag being delivered to an elevating platform, and means responsive to said detecting means for changing the position of said elevator valve opening means to prevent opening of said elevator valve when a bag is found to be absent whereby to prevent elevation of said elevating platform, said elevator valve opening means including an air circuit, a cylinder operated cam in said air circuit, a normally open solenoid operated valve in said air circuit, said solenoid operated valve also forming a part of an electrical circuit, said detecting means including an electric eye and a relay in said electric circuit for closing said solenoid operated valve to permit bleeding of said cylinder and retraction of said cam to prevent opening of the elevator valve when a bag is found to be absent.

9. In a continuously operated rotary vacuum filling machine, in combination, vacuum filling means including a plurality of vacuum filling heads, a plurality of elevating platforms cooperating with said filling heads for supporting flexible bags, pneumatically operated means for elevating the platforms to present the bags into operative relation to their respective filling heads, and pneumatically operated control means associated with each filling head including an air circuit and a container operated sensing valve in said air circuit arranged to be opened by the bag when the latter is elevated to its fully seated position in its filling head for actuating said vacuum filling means to initiate a filling operation, said pneumatically operated elevating means including an air supply and an elevator valve associated with each elevator to admit air to effect elevation of a platform when the valve is opened and to release air to permit lowering of the platform when the valve is closed, means normally positioned to open said elevator valve, means arranged in the path of said elevator valve for closing the same at the end of a filling operation, means for detecting the presence of a bag being delivered to an elevating platform, and means responsive to said detecting means for changing the position of said elevator valve opening means to prevent opening of said elevator valve when a bag is found to be absent.

be absent whereby to prevent elevation of said elevating platform including drive means for rotating said vacuum filling means, said drive means including an electric circuit and a motor in said circuit, a normally closed stationary switch in said circuit, a normally open shunt switch in said circuit, means controlled by said sensing valve in its closed position for opening said normally closed switch when an elevator fails to rise, and elevator operated means for simultaneously clos-

ing said shunt switch to prevent opening of the motor circuit when the elevator is initially maintained in its lowered position because a bag is absent, said normally open shunt switch remaining closed until said normally closed switch is returned to its normally closed position whereby to permit the machine to continue in operation with the elevator in its lowered position.
